HEATING SYSTEM

Charles W. Graves, Arlington, Mass.

Application January 27, 1943, Serial No. 473,720

2 Claims.

(Cl. 237—9)

This invention relates to steam heating systems of that class wherein heat is supplied periodically, or in cycles, to the radiators thereof under control of a room thermostat, mechanically operated dampers or the like.

In systems of the class referred to it has heretofore been common practice to equip each radiator with a thermostatic air vent valve of that type which permits the escape of relatively cool or cold air from the radiators as steam pressure is built up within the same, but which closes automatically when heated by the steam that is delivered to the radiators.

It is also true of such systems that during periods of idleness of the steam generator the temperature and pressure of the steam within each radiator would at times fall sufficiently low to cause the radiator air vent valve to open and admit relatively cold air to the radiator to recharge the system with air at atmospheric pressure before the commencement of the next heating cycle. This admission of cold air to the radiator at such times was objectionable, mainly for the reason that it reduced the temperature of the radiator and its contents at the expense of heat units.

My invention has for its principal object to obviate the objectionable feature just referred to and to provide an improved heating system of the class described so constructed and organized that when, during operation of the system, the pressure therein falls to slightly below atmospheric pressure during a period of rest of the steam generator, then pre-heated air at atmospheric pressure will be delivered automatically into the system as required to maintain the pressure therein approximately at atmospheric pressure so that no air is taken into the system through the radiator vent valves, said delivery of pre-heated air being effected independently of the room thermostat or other heater-controlling means.

Other features of the invention are hereinafter pointed out.

In the accompanying drawing:

Figure 1 is a view, more or less diagrammatic, showing a heating system constructed and operating in accordance with this invention.

Figure 2 is an elevation, partly in section, of one of the air vent valves hereinafter referred to.

Figure 3 is an elevation, partly in section, of one of the radiator vacuum air vent valves hereinafter referred to.

Figure 4 is a section on line 4—4 of Fig. 1.

The steam heating system illustrated in Fig. 1 of the drawing comprises a steam generator 10 provided at its base with a burner 11 equipped with a control box 12 connected by a circuit 13 with a room thermostat 14 located within one of the spaces or rooms to be heated. When circuit 13 is closed by thermostat 14 the burner 11 is in operation and when opened at the thermostat the burner is out of operation.

Generator 10 is made with a boiler 15 within which water is maintained at a predetermined level so as to provide a steam space 16 at the top thereof. This steam space is connected by risers 17 with the radiators 18 located within the spaces or rooms to be heated, the thermostat 14 being arranged within one of the latter. Adjacent to its radiator each riser 17 is provided, as usual, with a shut-off valve 19 which is open while the radiator is in use.

Each radiator 18 is equipped with a vacuum air outlet valve 20 (Figs. 1 and 3) which is preferably of a well known type that is in common use at the present time. A valve of the kind referred to is also illustrated in Fig. 3 of U. S. patent to Ferguson, et al., No. 2,062,565 dated December 1, 1936.

This type of valve comprises a base *a* to which is secured a casing *b* by means of a coupling ring *c*. An exteriorly threaded nipple *d* provided on base *a* is screwed into a tapped hole provided in its radiator and loosely confined within said nipple is one end of a syphon tube *e* which returns condensate to the radiator. At the top of casing *b* is provided an outlet port *f* formed with a valve seat at its inner end. Adjustably mounted within the base *a*, and extending below the same, is a tubular stem *g* which supports a pressure-operated bellows *h* disposed within casing *b*. This bellows abuts and supports a thermostatic float *j* provided at its top with a valve stem *k* co-operating with the inner seat end of outlet port *f*. The inner end of tubular stem *g* communicates with the interior of bellows *h* while its outer end communicates with the outside atmosphere.

The float *j* is supported by stem *g* and bellows *h* and usually has a small quantity of volatile liquid contained within. Thus when the float is cold the bottom thereof is concaved but when its temperature is raised by the presence of steam within the valve said bottom is caused to assume a convex shape due to the expansion of the fluid within the float and this elongation of the latter closes the valve *k*.

Because of the fact that atmospheric pressure

always exists within the bellows *h* the latter will be maintained in its normal unexpanded condition so long as the pressure within casing *b* is at or above atmospheric pressure, but when, during operation of the system, the pressure within said casing falls below atmospheric pressure then the bellows tends to expand and will act through float *j* to maintain valve *k* in its closed position. In other words the radiator valve *20* is open when the system is first started thereby to permit air to vent from the system as the pressure and temperature within the latter builds up and when this takes place heat is transmitted from the radiator to the thermostatic element *j*, Fig. 3, which then operates to close valve *k*. Thereafter, during the operation of the system the valve *20* remains closed and no air is permitted to enter at said valve when a vacuum develops within the system for reasons that will appear later.

Thus, valve *20* is open only while the system is being started up and then only until the steam reaches and heats its thermostatic float whereupon valve *20* is automatically closed by expansion of the float. Thereafter, so long as the system is in operation and regardless of pressure variations therein, the valve *20* will remain closed as will be made clear later.

The top of the boiler *15* is made with a threaded aperture into which is tightly screwed the lower exteriorly threaded end of an upwardly extending metal pipe *21* whose upper end is closed by a cap *22*. This pipe *21*, in the illustrated example, is a one-inch iron pipe about six feet long and it is maintained heated, particularly the lower end portion thereof, to a substantial degree by heat transmitted to it from the top of the boiler *15*, so that it serves as presently to be described not only as an air reservoir but also as an air heating retort.

At about eighteen inches above the top of generator *10* the pipe retort *21* is provided with a plurality of inwardly opening thermostatic air inlet valve units *23* (Figs. 1, 2 and 4) which may each be constructed as shown in Fig. 2.

Each air inlet valve unit *23* comprises a base *a'* into the top of which is telescopically fitted and secured the lower end of a sheet metal casing *b'*. At one side thereof the base *a'* is made with an exteriorly threaded nipple *d'* screwed into a tapped hole provided in pipe *21*. Nipple *d'* is tubular and its inner end communicates with the interiors of base *a'* and casing *b'*. Within this nipple is loosely confined one end of a small siphon tube *e'* for returning condensate to pipe *21*.

The top of casing *b'* is made with an inlet port *f'* whose inner end provides a seat for a valve *k'* forming part of a thermostatic float *j'* that is supported by an adjustable screw *g'*. A small quantity of a volatile liquid is provided within float *j'* so that when the float is cold or unheated the bottom thereof is concaved but when heated the expansion of the liquid causes said bottom to bulge or expand outwardly thereby moving valve *k'* into its closed position against the seat at the inner end of port *f'*. Air valves *23* of the type shown in Fig. 2 of the drawing are old and well known.

Since the capacity of the inlet port *f'* of each valve *23* is small I have found it convenient and desirable, when using the standard make, to employ a plurality of these valves as shown in Figs. 1 and 4, in order to afford ample inlet capacity.

During each period of idleness of burner *11*

the temperature and pressure of the steam within the system, including pipe *21*, steadily decreases and if and when the pressure passes slightly below the outside atmospheric pressure, then the accompanying proportionate reduction in the temperature of the top of boiler *15*, pipe *21* and the valves *23*, causes the latter to open and admit air to the lower hot vertical section of pipe *21* by which it is heated as it passes through the same into the steam space of boiler *15*.

This breaks the vacuum and immediately restores the pressure within the boiler to atmospheric, the pointer *31* of a steam pressure gauge *30* being returned from a negative position to its neutral position at zero on the gauge dial. Continued idleness of burner *11* results in the pressure within the system again falling to slightly below atmospheric and this is accompanied by the automatic delivery of more pre-heated air into the boiler through valves *23* and pipe *21*, thereby again restoring pointer *31* to zero position from a negative pressure-indicating position into which it is moved each time the pressure falls slightly below atmospheric.

Valves *23* are normally closed and remain so until the pressure within the boiler falls below atmospheric whereupon the relatively cool air in the upper part of pipe *21* expands downwardly and cools the valves *23* which thereupon open and admit air to the boiler which destroys the vacuum. The air thus admitted is preheated as it passes through the lower hottest portion of the pipe *21*.

In this way pre-heated air will be intermittently delivered into boiler *15*, and pointer *31* will continue to be slightly vibrated between zero position and a negative pressure-indicating position, so long as the burner remains idle.

During these air replenishing operations no cold air will enter the radiators *18* through the valves *20* for the reason that the latter are retained in their closed condition automatically by their bellows *h* each time the pressure falls below atmospheric.

When the burner *11* is again started by the room thermostat and the temperature of pipe *21* and vent valves *23* is raised, the latter are again closed and maintained so through expansion of their floats *j'*. This condition continues to exist until the burner is again stopped and the pressure within the system again falls to slightly below atmospheric or zero, whereupon the above described air replenishing action is repeated.

From the above description it will be observed that the radiator valves *20* are thermostatically closed when the system is first started up and that they are maintained closed during the air replenishing period. Also that the valves *23* are primarily temperature-controlled although their opening movements are assisted by outside air pressure when the pressure within the system falls to just below atmospheric.

The heated pipe *21* serves as a reservoir holding a volume of heated air some of which moves into the boiler *15* owing to expansion thereof as the pressure within the system declines during the first part of each period of rest of the burner and before the valves *23* open, while the hottest portion of pipe *21* that is between the vent valves *23* and the boiler serves as a retort-conduit to pre-heat the air that is admitted through said vent valves *23* after said valves open.

The cost of operating the above described system is greatly reduced from that entailed in operating the system with the pipe retort *21* elimi-

nated. One system operated by me and constructed as above described showed an operating cost of one and nine-tenths cents per hour while the same system without the pipe retort and constructed as heretofore showed an operating cost of three and one-half cents per hour.

While I have herein shown a room thermostat 14 as automatically controlling the generation of steam by boiler 15 so as to supply heat periodically to the radiators, it is to be understood that any other suitable means such, for example, as mechanically operated dampers, may be employed in lieu thereof to serve this purpose, said other means, of course, being appropriate to the type of heater employed.

What I claim is:

1. In a steam heating system of the character described, the combination with a radiator equipped with a normally closed thermostatic air outlet valve, a steam generator including heating means, a room thermostat for automatically controlling the operation of said heating means to supply steam periodically to said radiator, and a riser through which steam is delivered to said radiator from said generator, of a dead end reservoir having an outlet communicating with the steam space of said generator, said air reservoir being directly heated by the boiler of said generator and also having an air inlet communicating with the outside atmosphere, and a valve controlling said air inlet and itself controlled by the temperature of said reservoir and its contents so that immediately upon a fall of the pressure within the system to a predetermined point slightly

below atmospheric pressure said inlet-controlling valve automatically opens to admit air to the system to break the vacuum therein and prevent opening of said radiator outlet valve so that the latter is maintained continuously closed during normal operation of the system.

2. In a steam heating system of the character described, the combination with a radiator equipped with a normally closed thermostatic air outlet valve, a steam generator including heating means, mechanism for automatically controlling and operating said heating means to supply steam periodically to said radiator, and a riser through which steam is delivered to said radiator from said generator, of an air-heating reservoir consisting of a dead end length of metal pipe whereof one end is connected with, and communicates with the interior of, the upper portion of the boiler of said generator and whereof the opposite end is permanently closed, said pipe being provided intermediate its ends and at a predetermined distance away from said generator with an inlet, and a normally closed thermostatic valve controlling said inlet so as to open the latter for the admission of air to said pipe independently of said radiator valve and said mechanism whenever the pressure within said pipe falls to a predetermined point slightly below atmospheric pressure thereby to supply preheated air to said boiler to break the vacuum within the system and prevent entrance of air through said radiator outlet valve.

CHARLES W. GRAVES.
